Thomas Loud Philadelphia Pennsylvania

Letters Patent

The substance referred to in these Letters Patent and making part of the same containing a description in the words of the said Thomas Loud himself of his improvement in the compensating tubes of Piano Fortes.

To all whom it may concern. I do it know that I Thomas Loud of the City of Philadelphia in the State of Pennsylvania have invented an improvement in the mode of constructing and applying a compensation tube to a Piano Forte, and that the following is a full and exact description thereof. It is known to piano forte makers that what is called compensation tube was applied to piano forte's some years since in London. The compensation tube was applied for the purpose of resisting the strain of the strings by supporting the blocks to which their ends are attached and also by their expansion contraction to compensate that of the strings resulting from change of temperature. The tubes in that English instrument are made with flat ends which rest against metal plates firmly attached to the said blocks of the Piano Forte. from the manner in which they were constructed and fixed they were liable to spring if unsupported and to prevent this bias of wood was placed in direct contact with them in order to sustain them. by which arrangement the vibration of the instrument was in some degree checked and the tone ^{of course} injured. My improvement is generally but one compensation tube. I do not intend however to limit myself in this particular but to use two or more should I find it advantageous to do so. my claim to improvement not being dependent upon the number of tubes but upon the manner in which they are constructed and support the strain — When one tube only is used it must be made larger than when two or more are employed. I shall describe but one as a competitor will naturally beat me off in employing a greater number upon the same principle.

8953X

I take a tube of iron which may be about one sixteenth of an inch thick, and an inch and a half, in diameter, and either brighten and polish it, or cover it with a thin tube as sheet brass or other metal, drawn upon it, on each end of this tube I fix a cap usually of iron and having projecting points of iron or steel in their centres. One of these points is upon the projecting head of a screw tapered into the cap, these points pass into countersunk holes in ornamental cast iron blocks, one of which is usually cast in one piece with the metallic plate at one end and the other secured firmly to the block containing the rest pins at the opposite end. The particular manner of fixing them will depend upon the construction of the Piano Forte and upon the judgment of the workman. What I claim as my invention and wish to secure by Letters Pa. tent is the employment of points or cones to sustain the force in compressing tubes for Piano Fortes whether constructed precisely in the manner herein set forth or in any other producing the same result by analogous means.
